COMBINED AMUSEMENT AND VENDING
MACHINE

Clifford R. Carney, Miami, Fla.

Application December 18, 1933, Serial No. 703,018

19 Claims. (Cl. 221—146)

This invention pertains to a combined amusement and vending machine that is coin controlled, and employs, in miniature, the well known excavator mechanism, said machine being more especially designed for the vending of confectionery, similar commodities, and other objects in the nature of prizes.

The prime object of the invention is to provide a novel, simple, economical, durable, and efficient machine adapted to create its own automatic power by manually operated means, which is under the control of the operator at all times, the operation of which will furnish considerable amusement and interest.

Another object of the invention is to permit automatic operation only after a coin has been inserted in the coin mechanism, and to permit the automatic operation of the excavating mechanism at the will of the operator. In other words, there is no limited interval of time from the insertion of the coin until the excavator mechanism operates. As soon as the operator has developed the automatic power, by manual means, it is his privilege to position the excavating means over any object in the machine he desires to pick up, then at that time only he has the privilege of releasing the power that will operate the excavator mechanism.

Another object of the invention is to provide an automatic apparatus that is controlled manually, but which is not dependent upon any motors, or electric current that is usually employed to make a machine automatic, since this type of apparatus may be operated anywhere, and at any time, without any electrical or power connections, and yet will operate the excavating apparatus automatically.

Another object of the invention is to provide a machine that is economical to manufacture, and has no electrical stops, wiring, etc., to get out of order, since the assembly is reduced to such simplicity that the likelihood of defective operation is practically eliminated.

Further objects are to so construct my novel and improved machine that a boom is provided to which a miniature excavator bucket is attached, said bucket being positioned at the will of the operator only after a coin has been inserted in the coin device, and also only after a definite amount of power has been developed, by manual means, and after said power has been developed the operator may take any amount of time to position the boom, but when he has obtained the position desired he will release the power that will operate the excavator mechanism, and from

the moment he releases said power the apparatus is entirely automatic; the excavating means will pick up the desired confection or prize, clasp and hold it; the boom will automatically reverse its original arc, as predetermined by the operator, and the excavator bucket will at the extreme end of the reversed arc release the said confection or prize, and it will be caused to fall through a chute or opening and the operator may pick up the prize and retain same as his possession; to provide automatic operable means, but suitable power mechanism that is positively controlled by the will of any person who desires to operate automatic means that will accomplish moving, lowering, grasping, lifting, effecting a return lateral movement and releasing of articles by a suitable grappling element so as to deliver the commodities to a delivery chute for gravitational delivery to the operator.

The foregoing and such other objects as may appear from the ensuing description are accomplished by the construction, arrangement, location and combination of the several parts herein-after more fully described, illustrated in the accompanying drawings, and more particularly pointed out in the claims appended hereto, it being understood that slight changes in the precise form, proportions and minor details of the construction may be resorted to without departing from the spirit or sacrificing any of the advantages of the invention.

In the accompanying drawings forming a part of this specification it will be seen that:

Figure 1 is a side elevation of the combined amusement and vending machine, showing its exterior appearance.

Figure 2 is a plan view, showing its exterior appearance from above.

Figure 3 is a vertical section through the machine taken in the plane of the dotted lines 3—3, Fig. 2, looking in the direction of the arrows.

Figure 4 is a horizontal section through the machine taken in the plane of the dotted lines 4—4, Fig. 1, looking in the direction of the arrows.

Figure 5 is a vertical section through a portion of the machine taken in the plane of the dotted lines 5—5, Fig. 4, looking in the direction of the arrows.

Figure 6 is a vertical section through a portion of the machine taken in the plane of the dotted lines 6—6, Fig. 4, looking in the direction of the arrows.

Figure 7 is a vertical section through a portion of the machine taken in the plane of the dotted lines 7—7, Fig. 4, looking in the direction of the arrows.

dotted lines 7—7, Fig. 4, looking in the direction of the arrows.

Figure 8 is a vertical section through a portion of the machine taken in the plane of the dotted lines 8—8, Fig. 4, looking in the direction of the arrows.

Figure 8—A is a vertical section through a portion of the machine taken in the plane of the dotted lines 8—8, Fig. 4, showing an alternate method.

Figure 8—B is a vertical section taken through the machine in the plane of the dotted lines 8—8, Fig. 4, showing a second alternate method, and

Figure 8—C is a vertical section through the machine taken in the plane of the dotted lines 8—8, Fig. 4, showing a third alternate method.

In the embodiment of my invention it will be seen by reference to Fig. 1 that the numeral 10 designates a cabinet for the reception of the operating mechanism, and consists essentially of a box or cabinet-like container having glass windows 11 on one or more sides through which the upper interior of the cabinet may be viewed, and just below the lower edge of the glass 11 is a horizontally disposed floor 12, on which are placed the articles to be vended, and at the lower portion of said cabinet is another floor 12', the major portion of the operating mechanism being disposed between and supported by the said floors 12 and 12'. Leading from the upper portion of the cabinet from the floor 12 out to the front of the cabinet is a chute 13 terminating with a hopper 14 by means of which the article vended is transferred from within the cabinet to the operator, and projecting through the front of the cabinet is a conventional coin receiving device 15, a crank-handle 16, and a push revolve wheel handle 17 for the purposes hereinafter described.

Through a hole in floor 12 projects a derrick mast 18, on which is mounted a group of three sheaves 19, a boom 20 on which in turn is mounted a group of two sheaves 21, with lines 23 and 25 passing over two of the sheaves 19 and the two sheaves 21 and thence to a dredge-type bucket 24, while line 22 passes over one sheave 19 and thence is secured to boom 20.

Disposed beneath the floor 12 is the means for starting, controlling and operating the mast, boom and bucket above referred to. The handle 16 has a hollow shaft 26 projecting through the front side of the cabinet with a shaft 27 fitted concentrically therein, but not keyed or fastened. The mechanical connection between said handle or crank 16 with the shaft 27 is made through the medium of the ratchet 28, which by engaging hollow shaft 26 by means of pawl 29 mounted on collar 30, which is fast to hollow shaft 26, enables the operator to revolve shaft 27 in one direction only.

Mounted by means of a spline on shaft 27 is one-half of a clutch 31 which is shifted laterally along the axis of shaft 27 by means of a shifting ring 32. Also mounted on shaft 27 is a reel 33 that is caused to revolve with shaft 27 when half of the clutch 31 engages the other half of clutch which is an integral part of reel 33, said reel 33 being held in its lateral position on shaft 27 by collar 35, which is made fast to shaft 27, and further along on shaft 27 is another half clutch 36 with its shifting ring 37. The rear end of the shaft 27 revolves concentrically inside of shaft 38, and shafts 27 and 38 are mechanically connected when shifting ring 37 moves half clutch 36 laterally to mesh with half clutch 39 which is keyed to the front end of hollow shaft 38. Keyed to the

rear end of hollow shaft 38 is a bevel gear 40, which meshes with another bevel gear 41 that is keyed to the bottom of mast 18, said mast being mounted at its lower extremity in bearings 42 and 43, which are shown as being integral with the base casting 44 seated on the floor 12'.

A lever is provided to move the shifting ring 32; this lever 45 is pivoted at its lower end and mounted on base casting 44, as shown in Fig. 6. Pivoted at the curved portion of the lever 45 is another small lever 46, which transmits its movement to lever 45 through coil spring 47. The upper end of small lever 46 terminates with two beveled teeth 48 and 49; the upper one of these beveled teeth 49 engages with a ratchet 50 mounted on the end of the movable slide 15 of the coin receiving means, and the lower one of these beveled teeth 48 engages with a ratchet 51 which is stationary, being fast to the cabinet, and ratchet 51 holds lever 46 in position after it has been drawn forward by the movable ratchet 50.

Designed to slide up and down between two standards 52 and 53 is a weight 54; this weight is raised by a cord 55 which is attached to the top of the weight by cleat 56, and passes over sheaves 57 and 58, and is coiled on the reel 33. Also mounted in a loose-fitting groove in weight 54 is a standard 59 of rectangular section with ratchet teeth on its outside face made fast to horizontal floor 12'. To keep the weight from moving downward when reel 33 is free to turn on shaft 21, a ratchet 60 is provided, this ratchet being pivoted at shaft 61, which shaft or pin is fast to 62, and, in turn, is screwed to the top of the weight. In order to slow up the downward motion of the weight when it is free to descend, there is provided a hollow piston rod 63, see Fig. 8, the lower end of the piston rod terminating in a check-washer similar to the type used in bicycle and automobile air pumps, said check-washer 64 being mounted on a loose fitting piston head 65, which, as the weight is raised and permitted to descend, raises and lowers inside of cylinder 66, said cylinder being filled with oil or other suitable liquid forming a dash-pot.

The speed of the descent of the weight 54 is controlled by the needle valve 67 that governs the degree of the opening of the orifice 68, and said orifice controls the speed with which the oil below the check-washer 64 can pass out through ports 69 to the space in cylinder 66 above check-washer 64. The degree of opening of the needle valve is adjusted by the turreted nut 70 shown on the upper end of the needle valve stem 67, threaded in the upper part of weight 54, see Fig. 8.

On the opposite side of weight 54 from standard 59 is a slide 71, see Fig. 7, of rectangular section, and this slide moves freely in a groove formed in the side of weight 54, and is kept from dropping out by cleat 72, see Fig. 5. At the upper end of this slide is a pin 73, adapted to limit the downward movement of said slide with respect to the weight, the upper section of the slide being reduced, and into this reduced portion is mounted a latch, pivoted to 71 and 76, with a notch at 77 which hooks over the top surface of weight 54 through the action of spring 78. The lower portion of the slide 71 is provided with a ramp 79 that during the upward movement of 71 contacts with roller 80 and thereby causes a rotary motion to be imparted through roller arm 81 to shaft 82 to shifting-ring arm 83 and terminating in a lateral motion of clutch 36.

Fitted into the push revolve wheel handle 17 is a shaft 84 which is held normally shifted to

ward the front of the machine by a coil spring 85, see Fig. 4. On this shaft 84 in front of ratchet 60 is secured a disk 86, and just in front of latch 74 is fastened a similar disk 87. The rear end of the shaft 84 has mounted thereon a drum or reel 88 to which is secured one end of cord 22, and on said reel cord 22 is wound when shaft 84 is revolved, so that when handle 17 is rotated in one direction the boom 20 is raised 10 and vice versa.

Mounted on the horizontal floor 12' opposite ratchet 60 is a vertical standard 99 of rectangular cross-section, the upper end of which is beveled at 90, and when weight 54 descends to 15 the proper elevation this bevel 90 contacts with a latch 91 and disengages latch 91 from ratchet 60, said latch being held in its normal position by spring 92 mounted on top of weight 54. Mounted on floor 12 slightly out of line with the 20 standards 52 and 53, and fastened at the top to yoke 94, is standard 95, see Fig. 5, and sliding up and down on this standard 95 is a sleeve 96 with 25 a flange 97 at its lower end and an eye 98 at its upper end. The diameter of flange 97 is such that it projects beneath weight 54 and will contact with same when the weight descends toward the lower position, and made fast to the eye 98 is a cord 99 that runs over sheave 100 and thence to the bull-wheel 101 keyed to mast 18. 30 Fastened to a V-shaped slot in the side of weight 54 is a rack 102 which meshes with a pinion 103, and as weight 54 rises and falls the vertical motion of the rack 102 imparts a rotary motion to pinion 103, first in one direction then the other 35 direction with the upward and downward travel of weight 54. This pinion is free to turn on shaft 104 while weight is traveling upward, and if weight 54 moves upward sufficiently to carry rack 102 upward enough teeth to cause one complete revolution of pinion 103, then the pawl 105 will engage the one tooth in flange 106 which is 40 part of pinion 103, and said pinion will transmit its rotary motion through flange 106, the pawl 105, and flange 107 to shaft 104 to which flange 107 45 is secured. Thus a device is provided for giving one complete revolution of shaft 104 for each descent of weight 54, provided that said weight has been raised the predetermined minimum. The ratio between length of rack 102, diameter 50 of pinion 103 and maximum possible upward travel of the weight has been worked out so that the single tooth in flange 106 will never engage pawl 105 but once for each operation of the machine, and an examination of the arrangement 55 shown will disclose that flange 107 will return to an identical position at the termination of each operation.

Keyed to the back end of shaft 104 is a crank arm 108, and on the outer end of this arm is a link 109 fastened to crank arm 108 by member 110, while on the other end of link 109 is a knob 111, and to member 110 and knob 111 are fastened cords 23 and 25, respectively, the difference in radii of 110 and 111 causing a variation in 65 the rate of travel of said cords 23 and 25.

Attached to the bottom of the horizontal floor 12 is a bell-crank lever 112, and to the end of the horizontal arm of said lever are attached two cords 113 and 114 which in turn attach to ratchets 70 50 and 51, respectively. When handle 17 is pushed in, disk 115 attached to shaft 84 engages the vertical arm of the lever 112, and through the medium of cords 113 and 114 lifts ratchets 50 and 51 to disengage them from the beveled teeth 48 and 49 75 of the small lever 46.

Figure 8—A illustrates a modified means and method of supplying a downward force to replace the weight 54. Instead of raising weight 54, a piston 116 fitted with a soft cup washer 117 compresses the air in the cylinder 66 beneath piston 116, thereby storing up energy in the form of compressed air.

Figure 8—B illustrates another slightly modified means or method of supplying a downward force to replace weight 54. This method makes 10 use of a coil spring 118 with which to store up the energy.

Figure 8—C illustrates a further modified means or method of supplying a downward force to replace weight 54. This method includes the 15 use of a piston and cylinder similar to those shown in Fig. 8—A, except, instead of compressing air to store up the required energy, a liquid is forced out of cylinder 66, through pipe 119, against a head provided by an elevated reservoir or sealed 20 air cushion.

The operation of my novel machine may be briefly described as follows:

The operator pulls out slide 15 of the coin receiving means until the circular perforation in 25 the slide provided for the coin is accessible, and he next pushes in slide 15, when the presence of the coin allows the slide to move ratchet 50 inwardly until it engages beveled tooth 49, and then he pulls slide 15 outwardly, thereby causing small 30 lever 46 to follow and lock ratchet 51 over the beveled tooth 48, while small lever 46, pressing against spring 47, moves lever 45 which actuates clutch 31 and mechanically connects shaft 27 with reel 33. The operator is now enabled to wind cord 35 55 on reel 33 and thereby raise weight 54, and when said weight 54 is in its down position slide 71 is resting on stop 120, and latch 74 is hooked over the top of weight 54, so the moment weight 54 begins to rise it lifts with it the slide 71. When 40 weight 54 has been raised a sufficient amount to insure the rack 102 having enough teeth above pinion 103 to give one revolution to shaft 104, then ramp 79 on slide 71 engages roller 80, which 45 rotates shaft 82 and engages clutch 39, thereby giving the operator control of the turning of the derrick mast so he can point the boom 20 in the direction desired at the same time he is winding the weight higher.

When the desired position has been reached 50 with the boom the operator turns handle 17, which, through the medium of shaft 84, gives control of the angle of the boom 20 with the mast 18, enabling the operator to raise and lower the boom 20 at will.

Now, when the bucket 24 is in position over the object which the operator has selected, the handle 17 is pushed inwardly, causing flanges to perform their functions as follows: Flange 86 trips ratchet 60, thereby unlocking weight 54 and 60 permitting it to begin its descent, and at the same time latch 91 locks the ratchet in release position; flange 115 pushes against bellcrank lever 112, thereby pulling upwardly on cords 113 and 114 and tripping ratchets 50 and 51, causing 65 clutch 31 to disengage; flange 87 pushes against latch 74, which holds slide 71 suspended from weight 54, thereby causing slide 71 to drop downwardly until caught by pin 73 coming in contact with the top of weight 54, and this downwardly 70 drop of slide 71 causes ramp 79 to pass beneath roller 80, thereby causing roller arm 81 to turn shaft 82 and disengage clutch 39. At this point the weight is slowly descending, and the operator 75 has control of the raising and lowering of the

boom 20 only, the other movements having been disengaged by the opening of the clutches 35 and 36. Weight 54 slowly descends until slide 71 comes to rest against stop 120 mounted on the end of dash-pot cylinder 66, then continues far enough lower to permit latch 74 on slide 71 to re-set. This feature enables the operator to get control of the turning of the mast 18 sooner, while still insuring his having raised weight 54 high enough to impart one revolution to shaft 104. The normal position of shaft 104 and crank 108 is shown in Fig. 3, in a downward position, thereby having strings or cords 23 and 25 pulled away from bucket 24, with jaws of bucket closed, and the bucket raised to its highest position near the upper end of boom 20. As crank 108 revolves, both cords are permitted to pass upwardly over sheaves 19 and bucket 24 descends; as said bucket descends, cord 25 being attached nearer the center of rotation of crank 108 than cord 23, a greater length of cord 23 will pass over sheave 19. This change in the relation between cords 23 and 25 causes a variation in distance between the bucket anchorages of these cords, shown in Fig. 3 of the drawings, and designated as 121 and 122, thereby causing bucket 24 to open during its downward movement and close during its ascent, gripping and holding the object below with which it has come into contact, and raising it upward toward the upper end of boom 20, and when weight 54 has descended until its bottom is slightly above floor 12' it comes in contact with the flange 97, forces sleeve 96 down standard 95 and causes cord 99 to pull the bull-wheel 101 around soon enough to have the bucket 24 over the opening to 13 slightly before the position of crank 108 changes the relation of cords 23 and 25 to cause the jaws of bucket 24 to release the object gripped between said jaws. Hence, when weight 54 has descended to the proper predetermined elevation, bucket 24 is over the chute 13 and the object is released, slides down chute 13 to be received by the operator, who removes it from the hopper 14.

Having thus described my invention, what I desire to claim and secure by Letters Patent is:

1. A combined amusement and vending machine, comprising a cabinet having a plurality of floors for supporting the commodities to be vended and the operating mechanism, said mechanism including a mast, a boom secured to the mast and a bucket, means for operating said mast, boom and bucket only after a coin has been inserted, a weight slidably mounted between upper standards, means manually operated for elevating the weight to a certain point cooperating with means for turning the mast, boom and bucket to the desired position, means connected with the weight for automatically locking the weight when elevated, means manually operated for releasing the weight, means connected with the weight reciprocally associated with a cylinder below for controlling the gradual descent of said weight, and means connected with and automatically operated by the weight adapted to deliver the desired commodity to the operator.

2. A combined amusement and vending machine, comprising a cabinet containing commodities, means including a mast, boom and bucket for picking up and delivering the commodity to the operator, a weight slidably mounted between vertically disposed standards, a manually operated shaft having operative connections therewith for elevating the weight to its proper point cooperating with means for turning the mast,

boom and bucket to the desired position, means for controlling the descent of the weight consisting of a piston rod connected with the weight having a reciprocating movement within a cylinder disposed below, said weight by its gradual descent when released being adapted to operate means for delivering and releasing a commodity to a delivery chute for gravitational delivery to the operator.

3. A combined amusement and vending machine, comprising a cabinet containing articles to be vended, means including a mast, a boom secured to the mast and a bucket for picking up and delivering the articles, a weight slidably mounted between two upright standards, a manually operated shaft associated with means operatively connected with the shaft for elevating the weight to a predetermined height, cooperating with means for moving the mast, boom and bucket to the desired position, means connected with the weight and operatively connected with means disposed below the weight for controlling the descent of said weight, automatically operated means connected with the weight for locking it in its elevated position, a manually operated shaft provided with means for releasing the weight, and means connected with the weight operated by the gradual descent of the weight for causing the article to be vended to be automatically delivered to the operator.

4. A vending machine of the character described including a cabinet, a mast, boom and bucket supported within the cabinet, said boom being pivotally connected to said mast, means connected to the boom, bucket and mast for grasping, lifting, conveying, and releasing articles at the point of delivery of the articles, a slidably mounted weight, a manually operated shaft connected with means for elevating the weight to a predetermined point cooperating with means for turning the mast and boom to the desired position, means connected with the weight for automatically locking it when elevated, said weight when released being adapted to automatically operate said mast and boom and all of the several parts connected therewith.

5. In a vending machine, a cabinet having an upper floor secured therein upon which the articles to be vended are displayed, a delivery chute having a receiving mouth extending through said floor adjacent one side of the cabinet, delivering mechanism including a mast, a boom secured to the mast and a bucket, for grasping, lifting, conveying and releasing the article to be vended above the delivery chute, a slidably mounted weight disposed below the upper floor, manually operated means having operative connections therewith for elevating the weight cooperating with means for moving the mast and boom to the desired position automatically operated means connected with the weight for locking said weight when elevated to a predetermined point, manually operated means for releasing the weight, said weight when released serving to automatically operate the mast and boom with all of the several parts connected therewith.

6. In a vending machine, a cabinet provided with an upper floor and a lower floor, articles to be vended being disposed upon the upper floor, a mast supported by the lower floor having a boom secured thereto and a bucket connected therewith for delivering the article to be vended, a slidably mounted weight disposed between standards, manually operated means disposed between said floors for elevating the weight to a predetermined

- mined point cooperating with means for simultaneously turning the mast and boom to the desired position, means connected with said weight for automatically locking it in its elevated position, means for releasing the weight at the will of the operator, said weight when released being adapted to automatically operate the mast and its connections for the proper delivery of the article to be vended to the operator.
- 5 7. A vending machine of the character described, comprising a cabinet, upper floor for supporting articles to be vended secured within the cabinet, a lower floor secured within said cabinet, a mast supported upon said lower floor and projected above the upper floor having a boom pivotally secured thereto, means for grasping and delivering the articles to be vended connected with said mast and boom, a weight mounted slidably between two standards, a manually operated shaft having operative connections therewith for elevating the weight to a predetermined point cooperating with means for turning the mast and boom to the desired position, means connected with the weight for automatically locking the weight when elevated, a manually operated shaft having means for releasing the weight, said weight when released causing the automatic operation of the mast and boom and all connections therewith for the proper delivery 10 of the article to be vended.
- 10 8. A vending machine of the character described, comprising a cabinet holding and displaying articles to be vended at its upper portion, means disposed within the cabinet for the proper delivery of the article to be vended, a weight slidably mounted, a manually operated shaft having connection therewith for elevating the weight to its proper point cooperating with means for turning the mast and boom to the desired position, automatically operated means connected with the weight for locking it when elevated, means actuated by a manually operated shaft for releasing the weight, said weight when released being adapted to automatically operate the mechanism for the proper delivery 15 of the article to be vended.
- 15 9. A vending machine of the character described, comprising a cabinet provided with articles to be vended disposed within its upper portion, a lower floor secured within the cabinet, a mast supported by said lower floor projecting above the said articles, said mast being provided with means for delivering the article to be vended to the proper delivery point, a weight slidably mounted, a manually operated shaft operatively connected with means for elevating the weight to a predetermined point cooperating with means for simultaneously moving the mast to the desired position, means actuated by a manually operated shaft for releasing the weight, said weight when released being adapted to operate the mast and its connections for delivering the article to be vended.
- 20 10. A vending machine of the character described, comprising a cabinet for supporting articles to be vended, means disposed within the cabinet for picking up, conveying, releasing, and delivering the article to be vended at the proper point of delivery, a slidably mounted weight, a manually operated shaft disposed within the lower portion of the cabinet with means connected thereto for raising said weight within said cabinet to a predetermined height cooperating with means for moving the said delivery means to its desired position, said weight when released 25 being adapted to automatically operate the said picking up, conveying and releasing means.
- 25 11. A vending machine of the character described, comprising a cabinet for holding articles to be vended, means for grasping, lifting, conveying and delivering the articles to be vended, a slidably mounted weight disposed between two standards, a manually operated shaft disposed near the bottom of said cabinet for raising the weight to a predetermined height cooperating with means for turning the said delivery means to its proper position, automatic means for locking the weight when it has reached the required height, manually operated means for releasing said weight at will of the operator, said weight being adapted to operate the said grasping, lifting, conveying and delivering means for delivery 30 of the article to be vended.
- 30 12. A vending machine of the character described, comprising a cabinet containing articles to be vended, means for grasping, lifting, conveying and delivering the article to be vended to the proper point of delivery a slidably mounted weight disposed between vertical standards, a manually operated shaft having mechanism connected therewith for raising the weight to a predetermined height within the cabinet cooperating with means for turning said delivery means to its desired position, manually operated means for releasing said weight, said weight and its connections being adapted to automatically operate said means for delivering the article to be vended.
- 35 13. A vending machine of the character described, comprising a cabinet provided with a support for articles to be displayed and vended, a lower floor secured within the cabinet, means for grasping, lifting, conveying and delivering the article to be vended to the proper point of delivery, a slidably mounted weight a manually operated shaft disposed above the lower floor, said shaft being provided with means connected thereto for raising said weight to a predetermined height cooperating with means for turning said delivery means to its desired position, means for automatically locking said weight in its raised 40 position, manually operated means for unlocking said weight at the will of the operator, said weight being allowed to descend slowly and by such descent automatically operate said grasping, lifting, conveying and delivering means.
- 40 14. A vending machine of the character described, comprising a cabinet having an upper chamber for the reception of the articles to be vended, a lower chamber for the reception of the major portion of the operating mechanism, means for grasping, lifting, conveying and delivering articles to be vended, a weight slidably mounted within the lower chamber a manually operated shaft disposed within said lower chamber provided with means for lifting a weight to its predetermined height within the lower chamber cooperating with means for turning the delivery means to its desired position, means for automatically locking said weight when raised to the proper height, manually operated means for releasing said weight when desired, said weight by a slow descent being caused to automatically operate the said grasping, lifting, conveying and delivering means.
- 45 15. A combined amusement and vending machine, comprising a cabinet containing articles to be vended, means for delivering the articles to the operator, a slidably weight mounted between standards, a manually operated shaft and operative means connected therewith for elevat-

- ing the weight to a predetermined height cooperating with means for turning the delivery means to its desired position, automatically operated means carried by the weight for locking the weight when elevated, a manually operated shaft for releasing the weight, and means operatively connected with and automatically operated by the descent of said weight for properly actuating the delivery means.
- 10 16. A combined amusement and vending machine, comprising a cabinet containing articles to be vended, a mast, a boom secured to the mast and a bucket for delivering the articles to the point of delivery, a weight slidably mounted between standards, a manually operated shaft associated with means for elevating the weight to a predetermined height cooperating with means for simultaneously turning said delivery means to the desired position, automatically operated means connected directly to the weight for locking it when properly elevated, a manually operated shaft provided with means for releasing the weight, and means connected with and automatically operated by the gravitational action of said weight for actuating the delivery means.
- 15 17. A combined amusement and vending machine, comprising a cabinet containing articles to be vended, a mast, a boom pivotally secured to the mast, and a bucket for delivering the articles to the point of delivery, a slidably mounted weight disposed between standards, a manually operated shaft having means operatively connected therewith and to the weight for elevating the weight to a predetermined point
- 20 25 30 35
- means to the desired position, automatically operated means carried by the weight for locking the weight when elevated, a shaft provided with means for releasing the weight, and means connected with and automatically operated by the gradual descent of said weight for actuating the delivery means.
18. A combined amusement and vending machine, comprising a cabinet containing articles to be vended, means for delivering the articles to the operator, a weight slidably mounted between two standards, a shaft having operative means connected thereto and to the weight for elevating the weight to a predetermined height 10 15 20 25 30
- means to the desired position, means secured to the weight for locking it when properly elevated, means connected to a shaft disposed above the first named shaft for releasing the weight, and means connected with and automatically operated by the gradual gravitation of the weight for actuating the delivery means.
19. A combined amusement and vending machine, comprising a cabinet containing articles to be vended, means for delivering the articles to the operator, a weight mounted within the cabinet, a shaft having operative means connected therewith for elevating the weight cooperating with means for simultaneously turning the delivery means to the proper position, manually operated means disposed above said shaft for releasing the weight, said weight when released being adapted to actuate the delivery means by its gradual gravitation.

CLIFFORD R. CARNEY.
